US0D1025167S

(12) **United States Design Patent** (10) Patent No.: **US D1,025,167 S**
(45) Date of Patent: ** Apr. 30, 2024

(54) **TRANSFER ROBOT**

(71) Applicants: **HYUNDAI MOTOR COMPANY**, Seoul (KR); **Kia Corporation**, Seoul (KR)

(72) Inventors: **Han Wool Choi**, Seongnam-si (KR); **Jun Hwan Park**, Seoul (KR); **Seok Young Youn**, Seoul (KR); **Hun Keon Ko**, Anyang-si (KR); **Ho Seong Kang**, Seoul (KR); **Hyeon Jeong An**, Seoul (KR); **Gyu Jong Hwang**, Suwon-si (KR); **Soo Kyoung Kang**, Gunpo-si (KR); **Dong Jin Hyun**, Suwon-si (KR); **Geun Sang Yu**, Gunpo-si (KR)

(**) Term: **15 Years**

(21) Appl. No.: **35/517,389**

(22) Filed: **Apr. 28, 2023**

(80) **Hague Agreement Data**

Int. Filing Date: **Apr. 28, 2023**

Int. Reg. No.: **DM/229037**

Int. Reg. Date: **Apr. 28, 2023**

Int. Reg. Pub. Date: **Jun. 2, 2023**

(30) **Foreign Application Priority Data**

Dec. 2, 2022 (KR) 30-2022-0050727

Primary Examiner — Patricia A Palasik

(57) **CLAIM**

The ornamental design for a transfer robot, as shown and described.

DESCRIPTION

1. Transfer robot

1.1 : Perspective

1.2 : Front

1.3 : Back

1.4 : Left

1.5 : Right

1.6 : Top

1.7 : Bottom

Reproduction 1.1 is a perspective view of a transfer robot showing our new design; reproduction 1.2 is a front elevation view thereof; reproduction 1.3 is a rear elevation view thereof; reproduction 1.4 is a left side elevation view thereof; reproduction 1.5 is a right side elevation view thereof; reproduction 1.6 is a top plan view thereof; repro-

(Continued)

duction 1.7 is a bottom plan view thereof; The color deviations among the reproductions are due to shadow or light reflections.

1 Claim, 7 Drawing Sheets
